UNITED STATES PATENT OFFICE.

HORACE WYMAN, OF WORCESTER, MASSACHUSETTS, ASSIGNOR TO
CROMPTON & KNOWLES LOOM WORKS, A CORPORATION OF MAS-
SACHUSETTS.

WEFT-REPLENISHING LOOM.

No. 805,109.

Specification of Letters Patent.

Patented Nov. 21, 1905.

Application filed February 17, 1905. Serial No. 246,010.

To all whom it may concern:

Be it known that I, HORACE WYMAN, a citizen of the United States, residing at Worcester, in the county of Worcester and State of Massachusetts, have invented certain new and useful Improvements in Automatic Weft-Replenishing Looms, of which the following is a specification.

My invention relates to looms, and particularly to automatic weft-replenishing looms of the class shown and described in United States Letters Patent No. 600,053, of March 1, 1898, in which a magazine or reservoir of the well-known Northrop type (shown and described in United States Letters Patent No. 529,940, of November 27, 1894) is provided at one end of the loom, containing bobbins or filling-carriers of different colors, which are automatically supplied to the shuttles on the breaking of the filling or the substantial exhaustion of filling in the running shuttle in the usual and well-known way, and change or shifting shuttle-boxes are provided at the other end of the loom and connections are provided intermediate the shifting shuttle-boxes and the magazine or reservoir to regulate the movement of the magazine for the supply of filling of the desired color to the running shuttle, according to the movement of the shifting shuttle-boxes.

In the class of looms referred to filling-detector mechanism is ordinarily employed on the shifting-shuttle end of the loom to detect the substantial exhaustion of filling in the running shuttle, and there are connections intermediate said filling-detector mechanism and the transerrer mechanism of the filling-supply mechanism on the opposite end of the loom to cause the operation of the transerrer mechanism to supply new filling to the running shuttle in the well-known way.

The object of my invention is to improve upon the construction of some of the parts of a loom of the class referred to and more particularly to improve upon the construction of the magazine or filling-supply mechanism which carries the bobbins or filling-carriers and the operation thereof, as will be herein-after fully described.

In my improvements the filling-supply mechanism has preferably two compartments, each compartment consisting of guideways for a series of bobbins, and each series is preferably of a different color or character, and a

transerrer to transfer a bobbin directly from one of said compartments into the running shuttle when the lay is in its forward position. In case of two compartments for the bobbins one compartment will preferably be upon one side of the transerrer and the other compartment upon the opposite side, and the compartments will have a rocking or reciprocating movement. An abutting surface or stop is provided at the lower end of the compartments to retain the bobbins in each compartment and with the lowest bobbin in each compartment in such a position that it will be either in a position under the transerrer to be transferred into the running shuttle or will be automatically moved into position by the rocking movement of the compartments, according to the movement of the shifting shuttle-boxes, and when the active shuttle in one compartment of the shuttle-boxes has its filling practically exhausted and the transfer of new filling is about to take place.

In my improvements, as shown in the drawings and hereinafter described, a filling-supply magazine of the Northrop type is used, which is centrally mounted above the transerrer and has a rocking or reciprocating movement instead of a rotary movement, as is customary, and the two compartments for the bobbins are concentric with each other, forming two circular guideways within the periphery of the two end plates or disks of the magazine. One guideway is for the heads and the other guideway for the tips of the bobbins. The guideways of the compartments for the bobbins are preferably made open at their upper part for the free placing of the heads and the tips of the bobbins in the compartments, and the bobbins drop down by gravity within the compartments on opposite sides of the pivotal support of the magazine to the lower ends of the compartments or guideways. A single division is preferably employed between the guideways for the heads of the bobbins at the lower ends of the guideways, which forms a terminal or stop for the bobbins in each compartment, and the lowest bobbin in each compartment at its head bears against said stop. The lower ends of the guideways for the heads and the tips of the bobbins in each compartment are made open to allow of the passage of the lowest bobbin in either compartment when said bobbin is in position under the transerrer, and suitable

spring devices are provided to yieldingly hold the tips of the two lowest bobbins, one in each compartment, and a spring device is also provided for holding the head of the bobbin which is directly under the transferer and a device for positioning the bobbins longitudinally. In my improvements the compartments in the magazine for the bobbins may be used to carry a series of bobbins in one compartment of a different color from the series of bobbins in the other compartment, and the loom may be provided with shifting or drop shuttle-boxes at one end, with shuttles carrying colors of filling corresponding to those in the compartments of the magazine, and the magazine will be moved automatically, so as to place a bobbin of the same color under the transferer as is in the running shuttle when the transfer is required. This movement will be under the control of the pattern-surface, which pattern-surface will also control the movement of the shifting shuttle-boxes.

I have shown in the drawings sufficient parts of a loom of the class referred to with my improvements applied thereto and having a filling-supply magazine at one end and shifting shuttle-boxes at the other end and also a filling-detector mechanism at the same end with the shifting shuttle-boxes sufficient to enable those skilled in the art to understand the construction and operation of my improvements.

Referring to the drawings, Figure 1 is an end view of parts of a loom of the class referred to having my improvements applied thereto and looking in the direction of arrow *a*, Fig. 2. The shifting shuttle-boxes are shown in section. Fig. 2 is a plan view of some of the parts shown in Fig. 1. The warp-threads and woven fabric are shown in this figure. Fig. 3 is a central vertical longitudinal section through the filling-supply magazine, taken on line 3-3, Fig. 1, and also shows some of the operating connections looking in the direction of arrow *b*, Fig. 1. Fig. 4 is a vertical cross-section through the magazine on line 4-4, Fig. 2, looking in the direction of arrow *c*, same figure. Fig. 5 is a section on line 5-5, Fig. 2, looking in the direction of arrow *d*, same figure; and Fig. 6 is a section on line 6-6, Fig. 4, looking in the direction of arrow *e*, same figure. Fig. 7 is a detached view showing some of the parts shown at the right in Fig. 2. Fig. 8 corresponds to Fig. 7, but shows a different position of some of the parts; and Fig. 9 is a detached section on line 9-9, Fig. 7, looking in the direction of arrow *f*, same figure.

In the accompanying drawings, 1 represents the loom sides or ends; 2, the breast-beam; 3, the lay-swords, pivotally mounted at their lower ends; 4, the lay; 5, the lay-connectors to the crank-shaft 6.

7 represents two shifting shuttle-boxes at one end of the lay, carrying the shuttles 8,

with the bobbins 9 therein and supported on the upper end of the vertically-moving rod 10, which through connector 11 is connected with the lever 12, and said lever through link 12' is connected with the well-known box 70 motion of the Crompton type, which is shown and described in United States Letters Patent No. 600,488, of March 8, 1898, and which comprises a mutilated pinion or master-gear 13, fast on the bottom or cam shaft 14, a mutilated pinion 15, having the movable teeth in the ordinary way, by which it is thrown into and out of operative connection with the master-gear 13 through arm 16, mounted on a stud, and connector 17 to the rock-shaft 18, 80 mounted in suitable bearings 19, and connector 20 to the indicator pattern-lever 21, which extends over the rotary pattern-chain 22, made up of rolls and tubes, all in the usual and well-known way. 85

I have shown in the drawings, Figs. 1 and 2, a filling-detector mechanism located at the shifting-shuttle-box end of the loom and having in this instance two feelers adapted to enter the shuttle-boxes and detect the substantial exhaustion of filling therein and in case of the substantial exhaustion of filling in either shuttle-box to operate through intermediate connections the transferer at the opposite or filling-supply end of the loom 95 to supply new filling to the single shuttle at that end of the loom. The filling-detector mechanism referred to may be of any ordinary and well-known construction and operation; but I have shown in the drawings a filling-detector mechanism of the type shown in United States Letters Patent No. 665,845, to which reference is hereby made. In said patent the feelers and the feeler-frame have a vertical reciprocating movement with the 105 shifting shuttle-boxes as they are raised and lowered. I have shown in the drawings the feeler-frame carrying the feelers as having a pivotal motion. This pivotal motion of the feeler-frame carrying the feelers I do not 110 claim as my invention; but the same is made the subject-matter of another application for Letters Patent by me, the serial number of which is 259,870.

I will briefly describe the filling-detector 115 mechanism shown in the drawings.

The lower end of a connector 23 is connected with the vertically-moving box-rod 10, and the upper end of said connector 23 is pivotally connected to the inner end of the feeler-frame 120 24, which in this instance is shown as pivotally supported at 25 in an upright stand 26. (See Fig. 1.) The feelers 27, in this instance two in number, correspond in construction and operation to the feelers shown and described in said Letters Patent No. 665,845 125 and consist of pins free to have longitudinal movement within the center of a coil of wire, through which an electric current is adapted to pass by means of wires 28 and 29, leading 130

to the opposite poles of any suitable source of electric energy. Each bobbin 9 has a metallic band thereon, which when exposed by the substantial exhaustion of filling on the bobbin 5 attracts the end of a feeler 27 and draws it out of its support, as fully described in said patent, leaving an opening at the rear of the feeler for the entrance of the upper end of a detector-arm 30, having a hub 30' pivotally mounted on a pin 31. (See Fig. 1.) A downwardly-extending arm 32 from the hub 30' carries a pin 32' thereon, which is pivotally connected with a rod 33, (see Fig. 2,) which extends transversely across the loom and is 15 connected with mechanism at the opposite or filling-supply end of the loom. (Shown in Figs. 2, 7, 8, and 9, as will be hereinafter described.)

In connection with the filling-feeler mechanism above described I have shown in the drawings mechanism shown and described in said Patent No. 665,845 for positively operating the detector-arm 30 intermittently at regular intervals to move the same and the mechanism connected therewith to their normal position after a feeler has indicated for a change of filling, as above described. Said mechanism comprises a lever 35, centrally pivoted on a stud 36 and having its inner end 30 in the path of and engaged by a cam 37, fast on the bottom shaft 14 and held in engagement therewith by a spring 38. (See Fig. 1.) The opposite end of the lever 35 has pivotally attached thereto the lower end of a connector 39. The upper end of the connector 39 is pivotally connected with one arm of an angle-lever 40, pivotally mounted. The other arm of said angle-lever 40 carries a pin 41, on which is pivotally mounted the inner end of 40 a longitudinally-moving rod 42. The outer end of said rod 42 is supported and has a reciprocating motion in a stand 43. (See Fig. 2.) At predetermined intervals, according to the shape of the cam 37, preferably every other 45 pick, through the lever 35, connector 39, and angle-lever 40, the rod 42 is moved outwardly to engage the detector-arm 30 below its pivotal support and move the upper end of said arm inwardly against the action of the spring 34 to return the same and the mechanism connected therewith to their normal position after the feeler 27 has indicated for a change of filling, as stated above.

Fast on the bottom shaft 14 is a cam 44, 55 which engages and operates the lower end of the cam-lever 45, pivoted at 46. The upper end of the lever 45 extends in the path of and is adapted to engage the inner hooked end of the filling-fork 47, (see Fig. 2,) and in case of 60 the absence of filling will move back the filling-fork slide 48 and through intermediate connections operate the shipper-lever 49 to stop the loom in the ordinary and well-known way.

65 I will now describe the filling-supply mech-

anism shown in the drawings and embodying my improvements and to which my improvements particularly relate. In this instance the magazine or reservoir for holding the bobbins is of the Northrop type, above referred to, and is combined with the shifting shuttle-boxes at the opposite end of the loom through intermediate connections to be operated to supply filling according to the movement of the shuttle-boxes.

The lower end of a connector 50, Fig. 1, is connected to the vertically-moving box-rod 10, and its upper end is connected to one end of a lever 51, centrally pivoted at 51'. The opposite end of the lever 51 has pivotally and 70 adjustably attached thereto the lower end of a connector 52. The upper end of the connector 52 is pivotally attached to a pin 53 on one arm of the angle-lever 54. Said angle-lever 54 is pivotally mounted on a stud 55, 80 and the other arm of said angle-lever 54 is in this instance made forked or slotted at its end to receive one end of the connector 56. The other end of the connector 56 is adjustably and pivotally attached to one arm of an angle-lever 57, pivotally mounted on a stud 58. The other arm of the angle-lever 57 is pivotally connected to the upper end of a link 59. (See Fig. 3.) The lower end of the link 59 is pivotally connected to an arm 60, which 90 in this instance extends through an opening 61' in the stand 61, which is secured upon the breast-beam and by the bracket 62 to the loom-arch. The inner end of the arm 60 is fast on a rocking sleeve 62, loosely mounted 100 on a pin 63, secured to and extending out from the stand 61 and forming the pivotal support for the sleeve 62. (See Fig. 3.) Through the arm 60 and the intermediate connections to the vertically-moving box-rod 10 105 a rocking movement is communicated to the sleeve 62 in one direction or the other, according to the vertical movement of said rod 10 and the shifting shuttle-boxes connected therewith.

I will now describe the magazine for the bobbins shown in the drawings and which in this instance embodies my improvements.

Fast on the inner end of the sleeve 62, in this instance secured thereon by a set-screw 115 64, is a hub 65' of a circular plate or disk 65. (See Fig. 3.) The periphery of the disk 65 extends within an annular lip or flange 61''' on the edge of the plate or stand 61. (See Fig. 3.) The disk 65 has an annular lip or flange 65'' thereon, which in connection with the flange 61''' on the plate 61 forms guideways 65''' upon its outer surface near its circumference of curved shape, conforming to the curved shape of the disk 65. (See Fig. 125 4.) The guideways 65''' in this instance two in number and arranged upon the opposite sides of the axis or pivotal support of the disk 65, form compartments for the heads of the bobbins 9, which are placed therein from 130

- the upper side of the disk through an opening 65''' in the flange 61''' on the plate 61 for the passage of the heads of the bobbins. The bobbins 9 drop down by gravity in the 5 guideways 65''' on opposite sides of the disk 65 to the lower ends of said guideways. A stop or division 66, preferably a single stop or division, as shown in Fig. 4, is provided at the lower end of the guideways 65''' to form 10 a stop or terminal for the head of the lowest bobbin in each guideway. In this instance the stop or division 66 is a radial projection on the disk 65. The flange 61''' on the plate 61 is cut away or has an opening therein to 15 allow of the passing out therefrom of the head of the lowest bobbin therein, as shown in Fig. 4. When the head of the lowest bobbin in one guideway 65''' is in a position directly under the transferrer 67, as shown in 20 Fig. 4, it will be yieldingly held in position preparatory to being discharged from the guideway by the engagement of the trans- 25 ferrer therewith in the ordinary way, in this instance by a stationary plate 68, having grooves 68' on its upper side to position the head of the bobbin, and also by a spring-ac- 30 tuated pawl or supporting-arm 69, which is pivotally mounted on a pin 70 and has an ex- 35 tension 69' thereon, with a spring 71 attached thereto and to the plate 61. (See Fig. 1.)
- In connection with the plate or disk 65 for the heads of the bobbins 9 a second plate or disk 72 may be used for the tips of the bobbins 9. The disk 72 has a hub 72' thereon, 35 which is fast on the rocking sleeve 62, in this instance secured thereon by a set-screw 73. The disk 72 has guideways 72'' upon its inner side formed by two annular flanges 72''' of curved shape and corresponding to the 40 curvature of the disk 72 and also to the curvature of the guideways 65''. The outer flange 72''' has an opening therein at its upper part for the insertion of the tips of the bobbins into the guideways 72''. (See Fig. 45 5.) The outer flange 72''' also has an opening therein at its lower part for the discharge of the tips of the bobbins. (See Fig. 5.) There are in this instance two spring-blades 74, se- 50 cured at their upper ends to the lower part of the disk 72, with their lower free ends ex- 55 tending inwardly each one against and slightly under a tip of the lowest bobbin 9 in each compartment, as shown in Fig. 3, to yieldingly hold said bobbins at their tip ends.
- 55 The two sets of guideways 65'', as shown in the drawings, for the heads of the bobbins and 72'' for the tips of the bobbins form, in this instance, two separate compartments in a magazine of the Northrop type, above re- 60 ferred to, each compartment adapted to hold a series of bobbins, one series preferably being a different color from the other, which bobbins are inserted at the upper ends of the guideways and drop down by gravity to the 65 bottom thereof, and a bobbin in its lowest po-

sition in one or the other of the compartments when the loom is running is yieldingly held directly under the transferrer and ready to be transferred into the running shuttle on the substantial exhaustion of filling in the 70 running shuttle.

The transferrer mechanism may be of the usual and well-known construction in the class of looms with which my improvements are intended to be used and consists in this instance 75 of a transferrer-arm 75, secured upon a rock- shaft 76 and extending through an opening 61'' in the plate 61, having on its inner end the horizontal transferrer-arm 67, above referred to. (See Fig. 3.) The transferrer-arm 75 is operated to transfer a fresh bobbin 9 into the running shuttle on the substantial exhaustion of filling therein in any usual and well-known way and in this instance by the engagement of the bunter 77 on the lay with 80 the finger 78, pivotally mounted on the lower end of an arm 78', fast on the rock-shaft 76, when said finger 78 is raised into the path of the bunter 77, in this instance by means of the mechanism shown in the drawings, and par- 85 ticularly in Figs. 7, 8, and 9. The inner end of the longitudinally-moving rod 33, (see Fig. 9,) which is connected at its outer end with the detector-arm 30, as above described, is supported and moves in a side boss or pro- 90 jection 81' on a vertically-moving plate 81, supported on the inner side of the breast- beam. The vertically-moving plate 81 has a vertical opening 81'' therein, (see Fig. 9,) into which extends the upper end of a vertically- 95 moving rod 82, which is pivotally attached at its lower end to one arm of an angle cam-lever 83, pivotally mounted on a stud 84. The other arm of the angle-lever 83 carries a roll 83', which travels in a cam-groove in a cam 85, fast 100 on the bottom shaft 14. (See Fig. 7.) Through the rotation of the cam 85 an up-and-down motion at regular and predetermined intervals is communicated to the vertically-moving rod 82. A spring 86, attached to the lower end of 105 the frame 1 of the loom and its upper end to a projection on the vertically-moving plate 81, acts to return said plate to its normal lowered position after it has been raised. The upper end of the plate 81 has a slot therein, into 110 which extends a pin 79', fast on an arm 79 on the rock-shaft 76. Fast on the rock-shaft 76 is an arm 80, carrying at its lower end a link 80', having the hooked end adapted to extend over a projection 78'' on an arm 78'', extend- 115 ing down from a finger 78, which is pivotally mounted on the lower end of the arm 78'. A coil-spring 87 is connected with the finger 78 and acts to move up said finger to its opera- 120 tive position (shown in Fig. 8) when said fin- ger is released from engagement with the link 80' on the downward movement of the arm 80 through the operation of the spring 88 when the upward movement of the slide 81 releases the arm 79. When the detector-arm 30 is 125 130

5 moved back of one of the feelers 27, said feeler being drawn out of its normal position by contact with the band on the bobbin, the longitudinally-moving rod 33 will be moved to the right in Fig. 2 and to the left in Fig. 9 to extend in the path of the upwardly-moving rod 82. By reason of the end of the rod 33 extending in the path of the upper end of the rod 82 the upward movement of said rod 10 through the rotation of the cam 85 and the movement of the cam-lever 83 will move upwardly the slide 81 against the action of the spring 86 and allow the spring 88 to act to lower the arm 80 and move inwardly the link 15 80 to release the projection 78" on the finger 78 and allow the spring 87 to operate to raise the finger 78, as shown in Fig. 8, into position to be engaged by the bunter 77 (shown in Fig. 1) to cause the operation of the trans- 20 ferrer-arm 75 to supply fresh filling, all as will be fully understood by those skilled in the art.

It will be understood that the details of construction of my improvements may be varied, if desired, and my improvements in the 25 magazine or reservoir may be adapted to be applied to and used on filling-change-mechanism looms of different type and with or without the particular form of rotary magazine of the Northrop type shown in the drawings herein.

The term "compartment" as herein used is intended to include, broadly, any means in the magazine to guide a group of superposed 30 bobbins or filling-carriers in their movement to the discharging end of the magazine preparatory to the removal of the bobbins during the operation of the loom.

The term "bobbin" as herein used is intended to include any form of filling-carrier suitable for use in a filling-carrier magazine.

Having thus described my invention, what I claim as new, and desire to secure by Letters Patent is—

45 1. In a loom, the combination with a magazine having a plurality of compartments, each compartment to contain bobbins or filling-carriers, and a stop or terminal for the lowest filling-carrier in each compartment, of means 50 to move the compartments to place the lowest filling-carrier, in any one of the compartments, in position under the transerrer, to be transferred into the running shuttle, substantially as shown and described.

55 2. In a loom, a magazine having two compartments or guideways for the heads and tips of bobbins, and a stop or terminal for the lowest bobbin in each compartment, to hold a bobbin in a position ready to be engaged by the transerrer when the bobbin is brought under the transerrer, substantially as shown and described.

60 3. In a loom, a magazine having a rocking reciprocating motion, and two compartments 65 or guideways for the bobbins, and a stop or

terminal for the lowest bobbin in each compartment, and retaining means at the lower discharge end of each compartment for the lowest bobbin, to hold the same in position under the transerrer, and ready to be engaged by the transerrer and placed in the running shuttle, substantially as shown and described.

4. In a loom, a magazine having a central axis or support, and a reciprocating rocking motion, and means for rocking said magazine according to the movement of the shifting shuttle-boxes, and two compartments or guideways in said magazine for the bobbins, one compartment on one side of the axis of the magazine, and the other compartment on the other side, and a stop or terminal for the lowest bobbin in each compartment, and means for holding the lowest bobbin in the compartments in a yielding position under the transerrer, ready to be engaged by the transerrer and placed in the running shuttle, substantially as shown and described.

5. In a loom, a magazine having a reciprocating rocking motion, and two compartments 90 therein, with guideways for the bobbins, which drop down to the lower end of the compartments by gravity, and a stop or terminal for the lowest bobbin in each compartment, and a transerrer, extending between the two compartments, and above and adapted to engage the lowest bobbin in either compartment, according as said bobbin is moved under the transerrer by the rocking of the magazine, substantially as shown and described. 100

6. In a loom, the combination with a magazine having two compartments, with open ends for the introduction of bobbins, which drop down by gravity to the lower end of the compartments to a stop or terminal, and said stop or terminal and means for yieldingly holding the lowest bobbin in the compartments under the transerrer, of said transerrer pivotally supported outside of the magazine, and having its engaging end enter the open space between the two compartments, substantially as shown and described. 110

7. In a loom, a magazine centrally pivoted and having a reciprocating rocking motion, with guideways around its circumference for two sets of bobbins, which are located on different sides of the central vertical line of the magazine, and a single discharge-opening for a bobbin of either set of bobbins, substantially as shown and described. 115

8. In a loom, a magazine having compartments for the bobbins, which fall by gravity in the compartments on opposite sides of the transerrer, and means for holding the lowest bobbin in the compartments in yielding position under the transerrer, and means to move said compartments back and forth, to place a bobbin in either compartment under the transerrer, to be acted on by the transerrer, substantially as shown and described. 125 130

9. In a loom, shifting or changing shuttle-boxes at one end, a stationary shuttle-box at the other end, filling-detector mechanism on the same end as the shifting shuttle-boxes, 5 and connected therewith, connections intermediate the filling-detector mechanism and the transerrer mechanism, connections intermediate the shifting shuttle-boxes and the filling-change magazine, and said magazine 10 having two compartments for the bobbins, and a stop or terminal for the lowest bobbin in each compartment, to hold a bobbin in a position ready to be engaged by the transerrer, when the bobbin is brought under the 15 transerrer, substantially as shown and described.
10. In a loom, a magazine having two compartments or guideways for the heads of bobbins, and a stop or terminal for the lowest 20 bobbin in each compartment to hold the bobbin in a position ready to be engaged by the transerrer when the bobbin is brought under the transerrer, substantially as shown and described.
11. In a loom, a magazine having compartments adapted to guide bobbins or filling-carriers, and a stop or terminal for the lowest bobbin in each compartment to hold a bobbin 25 in position ready to be engaged by the transerrer when the bobbin is brought under the transerrer, substantially as shown and described.
12. In a loom, a magazine for a filling-change motion having compartments composed of 30 guides for two series of superposed filling-

carriers provided with terminals for holding a filling-carrier of each compartment in a yielding position, substantially as shown and described.

13. In a loom, a filling-change mechanism, having a magazine with compartments to contain two series of filling-carriers, shifting shuttle mechanism having two shuttle-boxes with compartments for shuttles, and intermediate mechanism between the filling-change 45 mechanism and the shifting shuttle mechanism whereby each compartment of the magazine will be moved into a position corresponding with a compartment of the shuttle-boxes, as the boxes are moved from one position to 50 another, substantially as shown and described.

14. In a loom, a transerrer, a filling-changing mechanism having a magazine with two compartments, each compartment having a series of filling-carriers therein, and shifting 55 shuttle mechanism having shuttle boxes or cells with shuttles therein, and intermediate mechanism between the filling-changing mechanism and the shifting shuttle mechanism, whereby when a shuttle-box has a filling of 60 its active shuttle practically exhausted, the compartment of the magazine having a corresponding filling, will have its terminal and a filling-carrier in position under the transerrer, substantially as shown and described. 65
